UNITED STATES PATENT OFFICE.

JOHN C. LINCOLN, OF CLEVELAND, OHIO, ASSIGNOR TO THE LINCOLN COMPANY, OF CLEVELAND, OHIO, A CORPORATION OF OHIO.

ELECTRICAL RECIPROCATING MECHANISM.

1,050,960.

Specification of Letters Patent. Patented Jan. 21, 1913.

Application filed August 12, 1904. Serial No. 220,468.

To all whom it may concern:

Be it known that I, JOHN C. LINCOLN, a citizen of the United States, resident of Cleveland, county of Cuyahoga, and State of Ohio, have invented a new and useful Improvement in Electrical Reciprocating Mechanism, of which the following is a specification, the principle of the invention being herein explained and the best mode 10 in which I have contemplated applying that principle, so as to distinguish it from other inventions.

My invention relates to electrical motor mechanism for effecting a reciprocating motion, its object being to secure a construction more efficient and economical than has heretofore been effected. Devices for electrically producing a reciprocatory motion have heretofore been constructed, but in so 20 far as I am aware, their efficiency has been so low as to render them impracticable from a commercial standpoint.

My said invention consists of means hereinafter fully described and particularly set 25 forth in the claims.

I may refer to the patents to Van Depoele, 450,543, April 14th, 1891, and to Marvin, 368,405, August 16th, 1887, as exemplifying the prior art and as constituting 30 the nearest approach thereof to my present improvements. In the one an electro-magnetic structure comprising a single coil and numerous magnetic circuit-closing parts, is designed to draw the piston into 35 the coil, and permit it to fall back upon cutting off the exciting current. The other patent shows a sub-divided solenoid acting alternately upon two associated magnetic cores, and controlled by an extraneous 40 switching-mechanism for effecting the reciprocation of said connected cores. The embodiment of my invention utilizes certain features set forth in these patents, combined in a novel manner with improvements 45 of my own. The present structure may be described in a preliminary way as comprising a series of exciting coils, forming a single coil-structure, sub-divided by alternating magnetic circuit-closing parts, which 50 preferably serve as well, the function of making electrical connection with their respective coils. Exterior to all is a magnetic shell or envelop intimately associated with the magnetic circuit-closing parts.

Within said coils, and the magnetic system as above set forth, is mounted a relatively short reciprocating core or movable iron body equipped with electrical contact-mechanism designed to excite only an alternating group of the coils positioned in advance 55 of the center of figure of the movable core. This movable member or core, accordingly forms part of complete magnetic and electrical systems synchronously traveling therewith in effect, to cause the rapid movement of the said core. Thus my improved reciprocating motor is distinguished in several important particulars, structurally set forth in the claims. The most salient of these may be contradistinguished from the 70 art by pointing out that a single relatively short core, acted upon alternately from either end by a group of exciting coils approximating but a fraction of its length, is mounted for reciprocation within the structure. By reason of the arrangement herein set forth, moreover, only the coils positioned to exert the maximum effect are successively maintained in circuit, while in any position of the traveling core or movable 75 body, the magnetic system successively accommodates itself for most effectively closing the lines of force produced, through the body of said core.

The annexed drawings and the following 85 description set forth in detail certain mechanism embodying the invention, such disclosed means constituting but one of various mechanical forms in which the principle of the invention may be used.

In said annexed drawings:—Figure 1 represents a longitudinal axial section of an electric motor device embodying my invention, portions cut by the axial plane being shown in elevation. Fig. 2 represents a 90 transverse cross-section of the inner portion of the device including the movable core, the section being taken upon the plane indicated by line 2—2 in Fig. 1, and viewed as indicated by the arrows. Fig. 3 represents a side elevation of the movable core and broken portions of conductor rods and a draft rod. Fig. 4 represents a transverse section of the inner portion of the device including the movable core, and 95 taken upon the plane indicated by line 4—4, Fig. 3, and viewed in the direction indicated by the arrows adjacent to this line.

Fig. 5 represents a similar section taken upon line 5—5 of said figure and viewed in the direction indicated by the arrows. Fig. 6, represents a side elevation of a modified 5 form of the invention, and Fig. 6¹ is a fragmentary diagram showing the serial connection of the coils and disks, indicating by dotted lines, the path of the movable core.

10 The two main elements of my invention as illustrated in the drawings, consist of an outer coil structure and an inner movable core, constructed in a manner hereinafter fully described. The construction and operation of the device is, broadly speaking, 15 substantially similar to that of an ordinary solenoid and movable core therefor. By means of certain modifications and improvements, however, I have been enabled to 20 overcome the difficulties heretofore encountered in utilizing the ordinary solenoid and movable core for effecting a reciprocating motion and attain an efficiency in my improved mechanism substantially equal to that obtained in the rotary 25 electric motors at present in use.

The outer or coil structure consists primarily of a series of coil-sections numbered from 1 to 19 inclusive in the drawing. 30 These coil-sections are co-axial as shown, and are separated as will hereinafter appear, by metal disks, the coils and disks being connected in series and arranged alternately with respect to each other in the direction of such coil action. The interior space formed by these coils and disks is lined with a contact surface consisting of alternately occurring conducting and insulating sections which are formed in the 35 following manner. Upon the interior surface of the rings and coil-sections are secured alternately occurring metal rings B and insulating rings b', as shown in Fig. 1. The metal rings, which are constructed 40 of iron, are placed midway between each two adjacent coils and are separated from each other by means of the insulating ring b', as shown. Two terminal iron rings B project beyond the terminal coils as shown, 45 forming terminal sections of said contact surface. As shown in the drawing each iron ring is provided upon its inner surface with a thin brass ring or lining b which, however, 50 may be considered a part of the iron ring in so far as concerns the purposes of this invention. The outer and inner diameters of the coils and intermediate paramagnetic or iron disks C are equal to each other as shown, and surrounding the outer surface of the 55 said coils and disks is a succession of iron rings b² equal in number and similar in longitudinal location to the rings B. These latter rings are also separated from each other by means of thin insulating rings b'² 60 as shown. The inner surface of each disk 65

C is in electrical contact with the middle portion of the ring B as shown, and the outer surface of such disk is similarly in contact with a ring b³. Each disk C and its two contacting rings including the brass lining may be considered one integral construction; in so far as its action and function are concerned, and may, in fact, be made integral with each other if desired. The number of disks C is equal to the 70 number of coil sections, so that at one end of the coil structure a terminal is formed by a disk, and at the other end of the structure a terminal is formed by the end of the terminal coil section, as will 75 be readily understood. Beginning with the coil section number 1 on the left, one end thereof is electrically connected with the end of terminal disk C, the other end of such coil being connected with the next following disk C, to which latter one end of the coil 2 is connected. All of the disks and coils are connected in a simflar manner so that it will be observed the entire series of coils and disks is connected electrically in 80 series. The conducting surface sections formed by the brass rings b, accordingly comprise a succession of contacts by means of which the coil may be tapped at various 85 points in the direction of the coil axis. The outer cylindrical surface of the coil structure is surrounded by a suitable insulating material d'. The outer cylindrical surface of the latter is surrounded by an iron casting D, which is slightly longer than, and 90 projects a short distance beyond the ends of the coil-sections as shown. These ends are threaded and into them are secured two 95 annular cap plates d whose inner diameters are equal to the diameter of the interior of 100 the contact surface or bore as shown. Intermediately of these caps and the coil structure so described are located respectively two annular insulating disks d² and d³, whereby it will be seen that in connection with the insulation d', the entire series 105 of coil-sections is thoroughly insulated excepting upon the interior of the bore. The extremities of the bore are closed by means of disks E and F, respectively, of wood or 110 other suitable insulating material. Secured to the disk E by means of suitable metallic sockets e are two conducting rods e' and e² which extend into the bore parallel with the axis of the latter, and almost throughout the entire length thereof. These rods, 115 for constructive reasons, are set in positions about 120 degrees apart, and equidistantly from the axis of the bore. 120

In the middle of disk F is formed an 125 aperture which is provided with a bushing f, forming a bearing for a draft rod g¹ to the inner end of which is secured the movable core G. The main or body portion g of this core is made of iron and is formed at its 130

respective ends with conical recesses g^3 . Into these recesses are respectively fitted two caps H and I, made of brass or other non-magnetic material, suitably insulated from the main or body portion and secured thereto by properly insulated screws h and i . Each cap is provided with an outer flange portion of a diameter substantially equal to the interior diameter of the bore or contact surface. The diameter of the body portion is made slightly less than the diameter of such bore, so that it will be seen the core may move through the bore resting upon the flange portions of the end caps H and I the edge of the latter being indicated at i^4 , Fig. 5. Passing through the core and parallel with the axis of the latter are two long bores g' g' , which receive the conducting rods e' and e^2 respectively, as shown. Rod e' is out of contact with or insulated from cap I and the body portion of the core extending, as it does, through the expanded opening i^5 and the insulating sleeve g^2 , but in electrical sliding contact with the cap H, as shown in Fig. 1. In a similar manner conducting rod e^2 is out of contact with or insulated from the cap H and body portion g of the core, but in electrical sliding contact with the cap I. Upon opposite sides of the cap H are formed two transverse slots h^6 , one of which intersects the bore g' receiving the rod e' , as shown in Fig. 1. In these slots are located respectively two spring contacts or brushes h^7 h^7 , which simultaneously maintain contact between themselves and the adjacent portion of the contact surface or bore of the coil and between themselves and the rod e' , as shown in dotted lines in Fig. 2. Two of these springs are provided as shown for the purpose of effecting an even pressure upon opposite sides of the core, and making multiple and hence effective contact. In a similar manner slots i^6 are provided in the cap I in which are located respectively two springs i^7 , one of which maintains contact between itself and said contact surface or bore, and between itself and the rod e^2 . The outer ends of the two conducting rods e' and e^2 are connected with two wires s and s' , connected with suitable terminals whereby either one may be connected by means of a switch S to the main wire s^2 . A second terminal f' of the main or line wire is connected with the bushing f and to the latter with draft rod g^4 , the latter being securely threaded or fastened into the main or body portion of the core, passing through the cap H and being out of contact with the latter, as shown. Upon opposite sides of the main or body portion g of the core, are formed two transversely located slots g^5 in which are located respectively two spring contacts or brushes g^6 which simultaneously maintain contact between themselves and the contact surface or bore of the coil structure and be-

tween themselves and the main or body portion g of the core as shown in Fig. 4.

The above described device operates as follows:—Assuming that the current is turned into the rod e^2 , and that the parts 70 occupy the position illustrated, such current will pass from the rod into cap I, spring contact fingers i^7 i^7 and thence into the coil section of winding number 8, through said winding and also through windings 7, 6 and 5, in series, to the ring B, connected with 75 number 5, thence through spring contact fingers g^6 g^6 to the body of the plunger, thence to the draft rod g^4 , bushing f and line wire f' . Under these conditions the longitudinal center of the active magnetizing coils lies on a transverse plane between sections 6 and 7 while the center of figure of the plunger lies on a transverse plane to the left of it or say about midway between sections 80 85 90 95 100

4 and 5. Now as the plunger moves forward in the direction of the arrow, Fig. 1, into the field, the contact fingers i^7 and i^7 will pass onto the ring B of winding number 9, thus bringing this new winding into circuit while at substantially the same time the contact fingers g^6 g^6 on the body of the plunger will pass off the ring B of winding number 5 thereby cutting this section out of the circuit and leaving number 6 as the last winding in circuit. As the plunger progresses this operation is repeated with each successive winding thereby always keeping the plunger partly projecting into a live group of coil-sections or solenoid. 105

It will thus be seen from the above description that successive groups of coil-sections are successively energized to form successive actuating solenoids, such groups being maintained substantially equal to each other in number of sections or length, and hence a magnetic field of substantially constant volume is caused to move synchronously with the core G, such core always, as before-mentioned, projecting partly into the active part of the coil. The core therefore always tends to move so as to cause its center of figure to coincide with the middle of the actuating group of coil-sections. Generally speaking the construction is such that a magnetic field is formed by means of a solenoid, a movable core provided partly projecting into the solenoid, and means provided for adding to the length of the solenoid at one end and concurrently subtracting from such 110 length to the other end thereof in the direction of movement of the core, the latter controlling the means for making the addition and subtraction. The said field is therefore substantially fixed relatively to the core, and movable relatively to the coil. In this manner it will be observed only the required number of coil-sections is permitted to remain in the electrical circuit so that the electrical resistance is reduced to a minimum. 115 120 125 130

and maintained substantially constant. During such described movement of the core and magnetic field each group of coils when active forms a solenoid having a substantially closed para-magnetic circuit including the core itself, the separating disks or partitions C opposite the core, rings B and b^3 , and the outer inclosing casing or jacket D. Each group of active coil-sections becomes a highly efficient solenoid by reason of the above described construction. At any particular point during the movement of the core, the return magnetic flow is always effected through that end of the core projecting from the particular solenoid then in action, so that the return portion of the magnetic circuit bears a substantially constant relation to the active solenoid whichever group of coil sections may be included in such solenoid.

The efficiency of a solenoid is dependent upon the electrical resistance of the solenoid circuit; the resistance of said circuit depends upon the cross-section and length of the conducting wire and hence varies inversely as the cross-section and directly as the number of turns; and the number of ampere turns which are employed to produce a given effect by means of a given current varies directly as the reluctance of the magnetic circuit of the solenoid. By means of my above described structure wherein a substantially closed para-magnetic circuit is always provided for each solenoid, I provide the low reluctance required. This effect is further enhanced by causing the ends of the disks, C, to be in contact with rings B, and b^3 , of the greatest practical depth whereby the area of the air gaps which are unavoidable in the magnetic circuit, is enlarged to a maximum and their reluctance reduced to minimum.

By arranging the magnetizing circuit in sections and connecting the same as described, counter-electro-motive force is developed only in those sections surrounding one end of the core. Electro-motive force will be developed in the coil-sections surrounding both ends of the core when the latter is in motion, and is a counter-electro-motive force in those coils only through which the main current is passing.

In order to reverse the above described movement of the core, it is only necessary to throw the switch so as to cause the current to pass through rod e' instead of rod e^2 , thereby shifting the magnetic field relatively to the moving core as will further appear. Under such condition it will be seen that as before contacts g^6 g^6 , will remain in the electrical circuit but contacts h^7 h^7 , are cut out, contacts i^7 i^7 being substituted for the latter in said circuit. The active group of coil-sections is now changed so as to cause the end of core G opposite that which in the pre-

vious operation projected into the field, to so project into the newly formed field. The motion of core G, or its tendency to move, is hence in the direction reverse to that previously described, the relation of the parts and operation being however exactly similar to those previously described as will be readily understood. Means for automatically throwing said switch may be provided to cause the core to reverse its movement at the ends of its respective strokes. Such means I shall describe in a separate application for U. S. Letters Patent on a specific application of my herein described invention. As shown the switch may be thrown by hand or by other extraneous mechanism not controlled by a moving part of the above described device. In Fig. 6, however, I have illustrated a simple form of means for automatically throwing such switch. In this means I have provided the stem g^4 , with a slot g^7 , whose extremities include between them an extension s^8 , with which the switch S may be provided, as shown. The length of the slot is such that the said extension will be engaged by the stem to throw the switch at the proper time to effect the reversal of the current as above described.

Other modes of applying the principal of my invention may be employed instead of the one explained, change being made as regards mechanism herein disclosed provided the means stated by any one of the following claims or the equivalent of such stated means be employed.

I therefore particularly point out and distinctly claim as my invention—

1. In electrical motor mechanism, the combination with a relatively movable member having a reciprocatory path, of means for creating a magnetic field about the forward end of the movable member when moving in one direction, and about the other end when moving in the opposite direction and means for advancing such field with said movable member, comprising traveling brushes thereon and interiorly positioned contacts engaged thereby, substantially as set forth.

2. In electrical motor mechanism, the combination with a sectional coil-structure of magnetic circuit-closing parts disposed between the coil sections; the same being interiorly faced with para-magnetic parts closely approaching each other to afford a large area for the flow of magnetic lines of force, and a movable body or armature mounted to reciprocate within said electromagnetic structure, substantially as set forth.

3. In electrical motor mechanism, the combination with a relatively movable member or core having a reciprocatory path of movement, a sub-divided coil-structure wherein said core is actuated, contact parts actuated by the core and positioned to con-

nect successively altering groups of the coil-
structure in circuit, positioned in advance of
the center of figure of said core, while mov-
ing in either direction, and magnetic circuit-
5 closing parts positioned along the path of
said core for successively closing the mag-
netic circuit therethrough, whereby the field
is caused to advance synchronously with
said core, substantially as set forth.

- 10 4. In electrical motor mechanism, the
combination with a coil-structure of a plu-
rality of taps or contacts subdividing the
same into numerous coil-sections, an arm-
ature mounted within the coil-structure to be
15 reciprocated therein, and contacts positioned
upon the armature to cut into circuit alter-
natively at either end, coil-sections approxi-
mately equal to one-half the length of the
armature and generally in advance of its
20 center of figure, during each stroke of the
said armature, substantially as set forth.

5. In electrical motor mechanism, the
combination of a circuit including a plu-
rality of coils, a plurality of para-magnetic
25 elements interposed between adjacent coils
forming parts of moving magnetic systems,
a movable member controlled by said coils,
and means controlled by said movable mem-
ber for successively including and excluding
30 coils from the circuit comprising traveling
brushes thereon and interiorly positioned
contacts engaged thereby.

6. In electrical motor mechanism, the
combination with a sub-divided coil, of
35 means for maintaining a constant fraction
of said coil active, a movable member con-
tinuously influenced, and partly surrounded
by such coil-fraction, means for changing
the location of the latter along the coil axis
40 synchronously with the movement of said
movable member, comprising traveling
brushes thereon and interiorly positioned
contacts engaged thereby, and means for re-
versing the location of said coil-fraction
45 relatively to said movable member.

7. In electrical motor mechanism, the
combination of a coil provided with a series
50 of successively located taps, a core movable
in said coil, three contacts carried by said
core and arranged to establish connection
with three of said taps respectively two con-
ductors, two of said contacts connected with
55 said conductors respectively, the third being
in electrical connection with one terminal of
a circuit and means for connecting either of
said two conductors with the other terminal
of the circuit.

8. In electrical motor mechanism, the
combination of a plurality of coil-sections,
60 of a plurality of conducting disks, one such
disk interposed between each two adjacent
sections, and serving as an electrical contact
for adjacent sections, said disks and coils
being connected.

65 9. In electrical motor mechanism, the

combination of a plurality of para-magnetic
conducting segments disposed between the
several coil-sections thereof, and having
their surfaces in line with one another, a
plurality of insulating segments separating
70 said conducting segments, said surfaces of
insulating and conducting segments forming
a continuous surface a plurality of coil-sec-
tions connected to said conducting segments.

10. In electrical motor mechanism, the
combination of a plurality of conducting
rings having their inner surfaces coaxial
with one another, a plurality of insulating
rings separating such surfaces, said surfaces
and the inner surfaces of said insulating
75 rings forming a continuous cylindrical bore,
a plurality of coil-sections coaxial with said
bore and a plurality of conducting disks
located alternately with said sections along
the bore axis, said disks and sections being
80 electrically connected.

11. In electrical motor mechanism, the
combination of a cylindrical surface form-
ing a bore and composed of a plurality of
alternately occurring surface sections of con-
ducting and insulating material, a member
90 movable through said bore, a conductor fixed
relatively to said cylindrical surface, and
contacts carried by said movable member
and engaging said surface at two successive
95 points, one of said contacts being electrically
connected with said conductor.

12. In electrical motor mechanism, the
combination of a cylindrical surface form-
ing a bore and composed of alternately oc-
curring surface sections of conducting and
insulating material, a member movable
100 through said bore, two conductors fixed rel-
atively to said cylindrical surface, and three
contacts carried by said movable member
engaging said cylindrical surface at three
105 successive points, two of said contacts elec-
trically connected with said conductors re-
spectively, and the third contact electrically
connected with said movable member and
110 insulated from the said two contacts.

13. In electrical motor mechanism, the
combination of a series of coaxial coil-sec-
tions, a series of alternately occurring con-
ducting rings and insulating rings upon the
115 interior of said series of sections and form-
ing a bore, each such ring provided or
formed with a conducting disk electrically
connected therewith, said disks and sections
being alternately arranged along the bore
120 axis and electrically in series, a metallic cas-
ing surrounding said coil-sections and insu-
lated from said disks, a core movable in said
bore, two contacts carried by said core, and
a metallic conductor, one of said contacts be-
125 ing electrically connected with said core and
arranged to contact said rings successively,
the other contact being insulated from said
first named contact and also arranged to
contact said rings.

14. In electrical motor mechanism, the combination of a series of coaxial coil-sections, a series of alternately occurring conducting rings and insulating rings upon the 5 interior of said sections and forming a bore, each ring connected or provided with a disk electrically connected therewith, said disks and sections being alternately arranged along the bore axis and electrically in series, 10 a metallic casing surrounding said sections and insulated from said disks, a core movable in said bore, three contacts carried by said core, arranged successively in the direction of the bore axis, and two conductors, 15 the intermediate contact being connected with said core and arranged to contact said rings, and the other two contacts being also arranged to contact said rings, said latter contacts being insulated from said core and 20 electrically connected with said two conductors respectively.

15. In electrical motor mechanism, the combination of a movable core, a set of active coil-sections surrounding one end of 25 said core, a set of inactive coil-sections surrounding the other end of said core, traveling brushes upon said core, co-acting stationary contacts connected with the coil sections, and means arranged to operate at the 30 end of the core's strokes for changing the active to inactive sections and the inactive to active sections.

16. In electrical motor mechanism, the combination of a magnetizing coil-circuit of 35 constant length, a movable core controlled by said coil-circuit to effect its reciprocation therein, and a symmetrical magnetic structure, comprising means for maintaining the area of the portions of the magnetic circuit 40 conducting the lines of force out of the core and into the core constant during each reciprocatory movement of the latter comprising

ing contact brushes carried by the core and co-acting contacts within the coils.

17. In a reciprocating electric motor, the 45 combination with a subdivided helix or winding forming the field-coil, of a paramagnetic movable member or armature mounted to reciprocate therein, conducting-contacts forming terminals of the subdivisions of the field-coil, brushes or traveling contacts carried by the armature positioned to direct current through successive portions of the field-coil effectively in advance of the 50 armature in its direction of movement, and adjacent magnetic conductors disposed along the path of movement of the armature in position to close successively the magnetic circuit therethrough during the movement 55 of the armature, substantially as set forth. 60

18. In a reciprocating motor structure, a plurality of serially-connected field-coils, magnetic-circuit closing parts alternating with portions thereof, a reciprocating armature-part of para-magnetic material actuated 65 by the former, and electrical-circuit closing mechanism or means for directing current through portions of the field-coil structure successively in advance of the center of figure of said armature-part, substantially as 70 set forth.

19. In electrical motor mechanism, the combination with a coil-structure consisting of a plurality of sections, of parts for closing the magnetic circuit, alternating with 75 said sections, and forming electrical contacts through which the coil structure receives its current.

Signed by me, this 3d day of August, 1904.

JOHN C. LINCOLN.
